UNITED STATES PATENT OFFICE.

ARTHUR J. BRIGGS, OF SYRACUSE, NEW YORK, ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,138,931.

Specification of Letters Patent. Patented May 11, 1915.

Application filed December 10, 1912. Serial No. 735,885.

To all whom it may concern:

Be it known that I, ARTHUR J. BRIGGS, a citizen of the United States, and resident of Syracuse, in the county of Onondaga and 5 State of New York, have invented certain new and useful Improvements in Type-Writing Machines, of which the following is a specification.

My invention relates to bearings for the 10 type bars or other moving parts of writing machines and the objects of the invention are to provide, first, improved bearings of the character specified, and, second, an improved method of assembling the same; or, 15 more specifically stated, to provide improved type bars and hangers and methods of assembling and fitting or adjusting said type bars and hangers.

To the above and other ends my invention 20 consists in the features of construction, combinations of devices and arrangements of parts hereinafter described and particularly pointed out in the claims.

In the accompanying drawing, Figure 1 25 is a side elevation of a type bar and hanger embodying my invention. Fig. 2 is a fragmentary front elevation partly in section showing a plurality of type bars and hangers and the segmental support therefor. 30 Fig. 3 is an enlarged fragmentary side view illustrating the hanger and the bearing portion of the type bar shown in Fig. 1. Fig. 4 is a horizontal sectional view taken on a plane indicated by the dotted line $\alpha-\alpha$ in 35 Fig. 3 and looking in the direction of the arrows at said line. Fig. 5 is a sectional view taken axially of elements of the type bar bearing or joint. Fig. 6 is a sectional view illustrating the method of assembling 40 the type bar bearing or joint.

Each type bar 1 is pivotally supported in a manner to be specifically described hereinafter on a U-shaped hanger 2 which is secured by a screw 3 to a support 4. Said 45 support in the present instance is shown as an upright segment, the type bars being circularly disposed at the front face of said segment and normally resting at their type ends on a curved rest 5 forward of said segment, the type bars being adapted to be 50 swung upward and rearward by any suitable mechanism to coöperate with the front face of the platen (not shown). This is the usual front-strike arrangement, but it is to 55 be understood that my improvements are

adaptable to other arrangements of type bars and hangers; and further that said improvements may be employed to provide bearings or joints for other moving parts of writing machines.

The bearing end portion of the type bar is shaped to provide a circular enlargement or head 6 which is formed with a slotted lug 7 to which is connected an element or link 8 comprised in the actuating mechanism, said link being received in the slot in said lug to which it is pivotally connected. The head 6 is formed with a circular opening or eye 9, the face of which is shaped to provide an internal V-groove, bearing surface or 70 race-way 10 for a set or plurality of anti-friction balls or rollers 11. The rollers or balls 11 also coöperate with an inner stationary bearing or race-way composed of a pair of bearing elements, coned disks or 75 pieces 12, the peripheries whereof are oppositely coned or beveled as indicated at 13. These faces 13 together with the V-groove 10 provide a four-point bearing for each ball. The disks 12 are formed with holes to 80 fit over a bushing or supporting and spacing sleeve 14 provided with a central circular flange or spacing device 15 with the sides of which the disks are adapted to engage as clearly shown in Fig. 5. As will be seen 85 from this figure the ends of the sleeve 14 project beyond the outer faces of the disks and are adapted to be spread or headed over so as to permanently connect the disks with the sleeve. The outer faces of the 90 disks are slightly depressed, countersunk or beveled around the holes as indicated at 16 so as to facilitate the heading of the sleeve, as a result of which operation the three 95 parts are rigidly fastened together and the relationship of the disks 12 permanently 100 fixed; that is to say, the parts are held in a fixed or set relationship so as to provide a unitary device, it being necessary to compress one of the parts comprised in said device or permanently alter the shape of or distort it in order to effect a variation in such relationship. The sleeve is preferably of brass or very soft steel while the disks 105 are of hardened steel. The sleeve 14 is bored out centrally as indicated at 17 to receive a pin or rivet 18 which connects the sleeve and through it the type bar with the hanger 2. The rivet is supported at its ends 110 in ears 2^a projecting rearward from the up-

per ends of the hanger and the outer ends of said rivet are upset or headed to prevent displacement of the parts after they have been assembled.

5 In assembling the parts comprised in my improved bearing or joint the balls 11 are arranged in the race-way 10, being prevented from dropping out by one of the coned disks 12 while it and its associate 10 sleeve 14 are held in place by the assembler. Then the other cone or disk 12 is arranged on the sleeve, the ends of which at this time, it will be understood, have not been upset, the sleeve being in the condition illustrated 15 in Fig. 5. The parts are then placed in a suitable assembling fixture and in register with two dies 19 (Fig. 6), the operating faces whereof have suitably shaped depressions or countersinks 20, the side faces of 20 said countersinks being sloped or inclined. Next the die faces are forced toward each other by screw pressure or otherwise and the inclined or beveled faces of the depressions 25 20 will engage with the ends of the sleeve 14, forcing these ends down toward the outer faces of the coned disks 12 and also outward laterally. The result will be that the ends of the sleeve will be spread, filling the countersinks 16 and slightly overlapping the 30 faces of the disks. This spreading permits the faces of the dies 19 to engage the outer faces of the disks 12 and press said disks toward each other. The flange or separating device 15 is made a trifle wide so that initially or prior to applying pressure to the 35 disks the bearing is a little loose, that is, the balls are not in close contact with the bearing surfaces 13 and with the race-way 10, said faces being too far apart at this time 40 to give a close fit. As a result of applying pressure to the disks through the dies 19 the flange 15 is squeezed and slightly compressed, lessening the distance between the bearing surfaces 13. During this compression 45 the spreading of the ends of the sleeve will continue so that when compression ceases the disks 12 will be tight on the sleeve. A very fine adjustment of the type bar may be obtained by employing the described 50 construction and assembling it in the manner described. During the time that the dies are gradually approaching each other the assembler swings the type bar back and forth with his fingers and is enabled to determine by the feel of the bar when the proper adjustment has been secured. At this instant he arrests the dies, thereafter removing the bar. At this time it will be understood that the ball bearing joint is completely assembled but that the rivet 18 is not in place. The type bar device composed of the member or type bar proper 1, the inner bearing or bearing member comprising the disks 12 and sleeve 14 and the interposed 55 60 65 balls, is self-contained, the balls preventing

the inner bearing from dropping out while said bearing itself prevents displacement of the balls. The assembler next arranges the type bar between the side walls of the hanger 2 and passes the pin or rivet 18 successively through the hole in one of the ears 2^a thereof, through the hole 17 in the sleeve, and through the hole in the other ear 2^a. The ends of the rivet are then upset, forcing the inner faces of the ears 2^a to engage 70 tightly with the upset ends of the sleeve 14, the result being that the bearing member or device comprising the sleeve 14 and the disks 12 is rigidly secured in the hanger 2. When the hanger is secured in place on the segment 4 by the screw 3 the bearing surfaces 13 provide a fixed bearing for the balls 11 on which said balls may run back and forth during actuations of the type bar. 75 80

Among the advantages of the described 85 construction are simplicity and economy. Furthermore a very fine and accurate adjustment of the ball bearing joint is obtainable prior to assembling the type bar in its hanger. If the joint becomes defective or 90 loose through wear or otherwise it may readily be repaired by substituting a new sleeve and re-assembling the parts in the manner described.

Various changes may be made without departing from my invention. 95

What I claim as new and desire to secure by Letters Patent, is:—

1. In a typewriting machine, the combination of a type bar provided with an eye, 100 anti-friction rollers therein, bearing elements within said eye with which said rollers coöperate, and a compressible spacing member on which said elements are mounted, said member and said elements being rigidly secured together under compression. 105

2. In a typewriting machine, the combination of a type bar provided with an eye, anti-friction rollers therein, bearing elements within said eye with which said rollers coöperate, a compressible spacing member on which said elements are mounted, said member and said elements being rigidly secured together under compression, a type bar hanger, and means for connecting said 110 spacing member to said hanger.

3. In a typewriting machine, the combination of a type bar member, a bearing member, anti-friction rollers between said members, one of said members comprising 120 two relatively adjustable parts for taking up lost motion in the bearing, and compressible means operative independently of said rollers to secure said parts set permanently in a fixed relationship obtained by forcing 125 said parts toward each other against the resistance of said compressible means, a type bar hanger, and means for connecting said bearing member with said hanger.

4. In a typewriting machine, the com- 130

5 combination of a type bar member, a bearing member, one of said members being provided with an eye and the other comprising two adjustable parts, compressible means for securing said parts permanently in a fixed relationship obtained by forcing said parts toward each other against the resistance of said compressible means, anti-friction rollers within said eye and coöperating with said parts, said means being operative independently of said rollers to fix said parts, a type bar hanger, and means for connecting said bearing member with said hanger.

10 5. In a typewriting machine, the combination of a type bar provided with an eye, anti-friction rollers therein, a pair of disks within said eye having inclined bearing faces with which said rollers coöperate, and a compressible sleeve provided with a device for spacing said disks apart, said disks and said sleeve being rigidly secured together under compression.

15 6. In a typewriting machine, the combination of a type bar provided with an eye, anti-friction rollers therein, a pair of disks within said eye having inclined bearing faces with which said rollers coöperate, a compressible sleeve provided with a device 20 for spacing said disks apart, said disks and said sleeve being rigidly secured together under compression, a type bar hanger, and means for securing said sleeve on said hanger.

25 35 7. In a typewriting machine, the combination of a type bar provided with an eye, anti-friction rollers therein, a pair of disks within said eye having inclined bearing faces with which said rollers coöperate, a compressible sleeve provided with a device 30 for spacing said disks apart, said disks and said sleeve being rigidly secured together under compression, a U-shaped hanger, and a rivet for securing said sleeve fixedly 40 between the walls of said hanger.

45 8. In a typewriting machine, the combination of a type bar provided with an eye, anti-friction rollers therein, a pair of disks within said eye having inclined bearing faces with which said rollers coöperate, and a sleeve on which said disks are mounted, said sleeve being provided with a central flange which spaces said disks, the ends of 50 said sleeve being spread to rigidly secure the disks in place thereon.

55 9. In a typewriting machine, the combination of a type bar having an eye formed with a V-groove, anti-friction balls within said groove, two oppositely coned bearing disks coöperating with said balls, and a sleeve of relatively soft metal on which said disks are mounted, said sleeve being provided with a compressible flange which spaces said disks and the ends of said sleeve 60 being upset to secure said disks in place.

10. In a typewriting machine, the combination of a type bar having an eye formed with a V-groove, anti-friction balls within said groove, two oppositely coned bearing disks coöperating with said balls, a sleeve of 70 relatively soft metal on which said disks are mounted, said sleeve being provided with a compressible flange which spaces said disks and the ends of said sleeve being upset to secure said disks in place, a U-shaped type 75 bar hanger between the walls of which said type bar is arranged, and means connecting said walls and passing through said sleeve.

11. In a typewriting machine, the combination of a type bar having an eye formed with a V-groove, anti-friction balls within 80 said groove, two oppositely coned bearing disks coöperating with said balls, a sleeve of relatively soft metal on which said disks are mounted, said sleeve being provided with a compressible flange which spaces said disks and the ends of said sleeve being upset to 85 secure said disks in place, a U-shaped type bar hanger between the walls of which said type bar is arranged, and a rivet connecting 90 said walls and passing through said sleeve, said rivet securing said sleeve in fixed relationship with said hanger.

12. In a typewriting machine, the combination of a type bar provided with an eye, anti-friction rollers therein, bearing elements within said eye with which said rollers coöperate, a compressible spacing member on which said elements are mounted, 95 said spacing member and said elements being secured together in a fixed relationship so as to provide a unitary device changeable only by altering the shape or structure of one of the parts comprised in said device, a type bar hanger, means for connecting said 100 spacing member to said hanger, a supporting member, and means for detachably securing said hanger to said supporting member.

13. In a typewriting machine, the combination of a plurality of type bars, each type bar being provided with an eye, anti-friction rollers in said eye, bearing elements within said eye with which said rollers coöperate, a compressible spacing member on 105 which said elements are mounted, said member and said elements being secured together in a fixed relationship so as to provide a unitary device changeable only by altering the shape or structure of said device, a support for said type bars, and means for detachably mounting each type bar together with its unitary device on said support.

14. In a typewriting machine, the combination of a type bar member, a bearing member, one of said members being provided with an eye and the other comprising two adjustable parts and compressible means for fixing the relationship between 120 said parts so as to provide a unitary device, 125 said parts so as to provide a unitary device, 130

- it being necessary after said parts have been once adjusted to alter the shape of said means in order to vary the relationship between said parts, anti-friction rollers within 5 said eye and coöperating with said parts, a supporting member, and means for mounting thereon the type bar contrivance comprising said type bar member, said varying member and said anti-friction rollers.
- 10 15. In a typewriting machine, the combination of a type bar provided with a race-way, a plurality of relatively adjustable parts composing a second race-way, rollers coöperative with said race-ways, and compressible means for fixing permanently the 15 relationship between said parts.
16. The method of assembling a roller bearing for a type bar comprising a race-way composed of a plurality of relatively 20 adjustable parts one of which is compressible, which consists in permanently fixing the relationship of such parts by altering the shape of said compressible part in such a way that the type bar may be turned back 25 and forth on its axis during such fixing operation, said parts as a result of said fixing operation being held against displacement either toward or away from each other except by an alteration in the shape or structure 30 of said means.
17. The method of assembling a roller bearing for a type bar comprising a race-way composed of a plurality of parts and of a device compressible at the opposite sides 35 of each of said parts to permanently fix the relationship between said parts by compression, which consists in compressing said device and fixing such relationship in such a way that the type bar may be turned back 40 and forth on its axis during the compressing operation.
18. The method of assembling a type bar device comprising a type bar proper having a race-way for anti-friction rollers, two parts 45 provided with inclined bearing surfaces, and a relatively soft spacing sleeve provided with a separating flange which maintains said two parts separated to such an extent that there is an initial looseness in the bearing, which consists in partially spreading or 50 upsetting the ends of the spacing sleeve and then forcing said two parts toward each other and compressing said flange until the looseness in the bearing is taken up.
19. The method of assembling a type bar 55 and hanger comprising a type bar proper provided with a ball race, two parts related to provide a second ball race, and a relatively soft spacing sleeve having a flange for maintaining the two parts initially separated so that there is looseness in the bearing, which consists in partially spreading or 60 upsetting the ends of the spacing sleeve, then completing the spreading operation and concurrently forcing said two parts toward each other, compressing said flange until the looseness in the bearing is taken up, then riveting said sleeve and the type bar hanger together.
20. In a typewriting machine, the combination of a type bar provided with a race-way, a plurality of relatively adjustable parts composing a second race-way, rollers coöperative with said race-ways, and a single piece coöperative with each of said plurality 75 of parts at the opposite faces of each part to fix the relationship of said parts permanently in respect to each other and also in respect to said piece, said piece in itself alone so fixing each of said parts.
21. In a typewriting machine, the combination of a type bar provided with an eye, anti-friction rollers therein, bearing elements within said eye with which said rollers coöperate, and a single piece on which 85 said elements are mounted, said piece serving both to properly space said elements apart and also to permanently fix or lock said elements on said piece.
22. The method of assembling a type bar 90 and a plurality of parts comprising a bearing device therefor, which consists in interlocking certain of said parts by compression so as to fix the relationships between all of said parts and provide a single unitary rigid bearing device, the compressing operation taking place prior to the securing of said type bar and said device in the type bar hanger so that the type bar may be turned 95 back and forth on its axis during the compressing operation.

Signed at Syracuse, in the county of Onondaga, and State of New York, this sixth day of December A. D. 1912.
